UNITED STATES PATENT OFFICE.

MARIETTA LINDEBERG, OF OCEAN GROVE, NEW JERSEY.

GARMENT.

1,305,911.

Specification of Letters Patent.

Patented June 3, 1919.

Application filed May 15, 1918. Serial No. 234,625.

To all whom it may concern:

Be it known that I, MARIETTA LINDEBERG, a citizen of the United States of America, residing at Ocean Grove, in the county of 5 Monmouth and State of New Jersey, have invented certain new and useful Improvements in Garments, of which the following is a specification.

My invention relates to garments and par-

10 ticularly to bloomer garments, the object of my invention being to combine in a garment of this type the modesty of a skirt effect with the freedom and comfort of a bloomer construction. The invention has an extended utility, inasmuch as the construction is 15 applicable not only to women's work garments, but also to bathing suits, gymnasium suits, riding habits, children's play suits, etc.

In the accompanying drawings,

20 Figure 1 is a front elevation of a garment in which my invention is embodied in one form;

Figs. 2 and 3 are sections on the lines 2—2 and 3—3, Fig. 1, respectively;

25 Fig. 4 is a rear elevation of the garment; Fig. 5 is an inverted plan thereof;

Fig. 6 is a plan of one of the plaits;

Fig. 7 is an elevation of the ankle cuff;

30 Fig. 8 is a broken elevation of a modified ankle cuff;

Fig. 9 is an elevation of a bathing suit in which my invention is embodied.

Referring to the drawings and particularly to Figs. 1 to 6 inclusive, the garment 35 here illustrated is a two-piece suit and comprises a blouse 10 and separate bloomers 11, the blouse being fastened thereto at the waistband 12 on the bloomers by means of snap fasteners 13, buttons, or other fastening device. The only features about the blouse which merit particular attention are:

40 first, the collar 14, which is cut high to permit it to be buttoned close and used with a necktie, or left open so that it may be rolled back like a sailor collar with a V-neck (indicated in dotted lines, Fig. 1); and, second, the forearm sections 15 of the sleeves, which are made independent of the upper sleeve sections 16 and secured thereto by snap fasteners 17. This permits the removal of the 45 forearm sections in hot weather, or for washing and the like, and, at the same time, enables them to be quickly attached when desired.

50 My invention is particularly concerned with the bloomers 11. These comprise the

usual full legs, gathered at the knee and sewed at their upper ends to the waistband 12. Each leg is preferably fashioned from a front piece 18 and back piece 19 sewed together at the outer and inner leg seams 20 and 21 and front and back body seams 22 and 23. To secure a skirt effect for the bloomers, I provide front and back box plaits 24 and 25, the upper portions of 55 which are narrower than the lower portions (see Fig. 6). The lower portion of each plait is extended on each side to form wings 26 and 27, into which the upper portion of the plait merges by the curve lines 28 and 29. The folded upper end of each plait is sewed to, or otherwise secured at, the waistband 12. The meeting edges 30 and 31 of the front plait are sewed into the front body seam 22 joining the upper portions of the 60 bloomer legs, the curved edges 29 and 30 following the crotch seam, while the outer margins of the wings 26 and 27 are sewed into the inner seams 21 of the bloomer legs and follow these seams down to approximately the knee gathers. The back plait 24 is similarly fastened in at the back of the bloomers. The lower edges of both the front and back plaits are preferably cut out at 32 to lessen weight and at the same time 65 permit greater freedom of action without detracting from the skirt effect, since the inner folds of the plaits fill the cut-out space 32 and cascade downward toward the bloomer knees. The width of the front plait 70 from tip to tip of the wings 26 and 27 is substantially equal to the combined length of the inner leg seams from the crotch to the point of attachment to the wing tips, so that the insertion of the plait does not 75 restrict the freedom of the bloomers in the least. The back plait 25 is somewhat fuller than the front plait to afford more room and give a better effect.

While the main feature of my invention 80 relates to the box plaits just described, I have also provided each leg of the bloomers with an ankle cuff 33—34 which extends from the knee gathers to the ankle or shoe top. These ankle cuffs may be detachably connected to the knee gathers or sewed on, as desired, although I prefer to have them attached by snap fasteners in the same fashion as the forearm cups of the blouse, since, in 85 many cases, they may not be desired.

110 Various modifications of the bloomers will readily occur to those dealing with the

garment. Some of these I have indicated. Thus, the box plaits need not be secured at their upper ends to the waistband, but may be shortened and attached at any point 5 above the crotch, as indicated at the dotted line 35 in Fig. 1. This construction is not as attractive in appearance as that first described, but serves the function of imparting a skirt effect to the garment. The lower 10 margins of the wing pieces 26-27 may be secured by snap fasteners, or in fact the whole plaits may be so secured in place, so that they may be readily detached when riding horseback. In Fig. 8 15 I have shown the ankle cuff in the form of a spiral puttee 36, provided at one end with snap fasteners 37 adapted to engage coöperating fasteners on the knee gathers 38.

In Fig. 9 I have shown a one-piece bathing suit 39 in which my invention is embodied. In this one-piece construction the box plait 40 is carried down from the neck the full length of the garment, front and back, and its lower edges are secured in like 25 manner at the inner side seams of the bloomers. The suit is open at the front after the fashion of a union suit, and the fastening devices 41 are so arranged as to be concealed beneath the plait. Various other 30 modifications will readily occur to those skilled in the art without departing from what I claim as my invention.

I claim:

1. In a garment of the type described, 35 bloomers having a front box plait extending from a point above the crotch of the bloomers to a point below the crotch and secured at its lower side margins to the inner sides of the bloomer legs.
2. In a construction such as that specified in claim 1, a box plait of greater width at its lower than at its upper portion.
3. In a construction such as that specified

Copies of this patent may be obtained for five cents each, by addressing the "Commissioner of Patents, Washington, D. C."

in claim 1, a box plait having wing-like extensions on its lower portion secured to the 45 inside of the bloomer legs.

4. In a bloomer, a front skirt-like element extending between the bloomer legs and attached at its top to the bloomer body above the crotch and having its lower outer margins 50 fastened to the inner sides of both bloomer legs.

5. In a bloomer, a front skirt-like element extending between the bloomer legs and attached at its top to the bloomer body and 55 fastened at its lower outer margins to the inside seams of both bloomer legs.

6. In a bloomer, a front skirt-like element extending between the bloomer legs and having a full upper portion, the upper side margins of which are attached at the front body seam of both bloomer legs and the lower side margins of which are attached at the inside 60 seams of the bloomer legs.

7. In a bloomer, a skirt-like element extending from a point above the crotch of the bloomer legs to a point below the crotch and secured at its lower side wings to the inside 65 seams of the bloomer legs, together with narrow extensions of said bloomer legs attached to the latter below the point of attachment of the lower margin of said skirt-like element.

8. In a bloomer, front and back skirt-like elements extending between the bloomer legs 75 and attached to the bloomer body above the crotch, each element being secured at its lower outer side margins to the inside of the bloomer legs below the crotch, the lower 80 portions of said skirt-like elements being of greater width than the upper portions thereof.

In testimony whereof I have signed my name to this specification.

MARIETTA LINDEBERG.
